UNITED STATES PATENT OFFICE.

EDWARD D. CUNDELL, OF PATERSON, NEW JERSEY.

PORTABLE FIRE-SHIELD.

SPECIFICATION forming part of Letters Patent No. 717,173, dated December 30, 1902.

Application filed May 10, 1902. Serial No. 106,847. (No model.)

To all whom it may concern:

Be it known that I, EDWARD D. CUNDELL, a citizen of the United States, and a resident of Paterson, in the county of Passaic and State 5 of New Jersey, have invented certain new and useful Improvements in Portable Fire-Shields, of which the following is a specification.

My invention consists of a shield of asbestos fabric or other fireproof material which can be transported from place to place and readily attached on the side of a building.

My object is to prevent the spread of fires in thickly-populated districts by raising the 15 fire-shield on the side of a house adjoining the one that is on fire and prevent it from being ignited.

My special object is to provide a portable appliance which can be readily transported 20 from place to place by the fire-department or salvage corps, easily and speedily erected on the side of any building, and positively preventing the spread of flames into the adjoining house where the shield is applied, which 25 will be more fully explained by the accompanying drawings, in which—

Figure 1 represents an end elevation of fire-shield mounted on supports ready to be spread over the side of a building. Fig. 2 is a side 30 elevation of same, part in section. Fig. 3 represents an end elevation of the fire-shield placed between two buildings and spread over the side of the one to be protected from the flames from the other. Fig. 4 represents an 35 end elevation of the fire-shield as applied to a factory building.

A and B are the shields, made of asbestos or other flexible fireproof material, rolled around a mandrel or bar C in double fold. 40 The ends of mandrel C are provided with journal ends a and b, mounted in bearings c, which are attached to the supporting-legs d and f by the swinging block g. The said supports d and f are pivotally attached to block 45 g, so they can be folded together for transportation and held in the extended position by the stay-hook e.

In applying the fire-shields A and B to a building the said shield, which has been previously rolled upon mandrel C, is carried in 50 position between the buildings and mounted

on the supports d and f, which are stayed by the guy-ropes h, which securely hold the supports in a vertical position, with the roll of fire-shield mounted on top of same. The 55 shield A is then raised up on the side of the building over the roof, as shown in Fig. 3, and secured by the stay-line p in any suitable manner. At the same time that the shield A is being raised the shield B will be unwound and lowered toward the ground and secured by the line S to stake O or any other suitable object. The cap of the bearing c is hinged on one side at u and provided with adjusting-bolt t and cam-lever k, to 60 which the cord w is attached, and any amount of friction desired to check the rapid unwinding of the roll may be obtained. When all danger from the fire is over, the fire-shields A and B can be rolled up on mandrel C by the 65 hand-chain x, operating the sprocket-wheel D on one end of the mandrel C. Then the roll of fire-shields can be lowered, the bearings c, with supports d and f, removed from the mandrel-journals a and b, and folded up, 70 when all is ready for transportation to another point when desired.

In some instances, especially on factory buildings, it is desirable to have the fire-shields permanently attached to the building. 80 This I accomplish by mounting the roll of fire-shield and mandrel C in fixed bracket-bearings F, attached to the outside of building, as shown in Fig. 4, which is operated in the same manner as described for the portable appliance. 85

When rolled up and not in use, I provide a flexible cover E to protect the fire-shield from the weather. This cover E will lie up against the building when the shield A is 90 drawn up to the roof of building and readily replaced in position when the shield is again rolled up.

Thus it will be seen I have a practical device which will be a sure preventive of the 95 spreading of fires from one building to another and prevent disastrous conflagrations.

What I claim, and desire to secure by Letters Patent, is—

1. A portable fire-shield of asbestos or other 100 fireproof material, rolled upon a mandrel in two parts, said roll mounted on pivoted sup-

ports, one part to extend above the roof of the building, the other part to extend to the ground to protect the building from fire, substantially as and for the purpose specified.

5 2. A portable fire-shield of asbestos or other fireproof material, rolled upon a mandrel and mounted on journaled supports, in combination with journal - bearings, pivoted to upright supports; which can be folded up for

transportation, substantially as and for the purpose specified.

Signed at New York, in the county of New York and State of New York, this 8th day of May, A. D. 1902.

EDWARD D. CUNDELL.
